CLAIM

The ornamental design for a fish-holding device for performing tests with fish, as shown and described.

DESCRIPTION

FIG. 1 is a front side view of a fish-holding device for performing tests with fish, in accordance with one embodiment or aspect of the present design;

FIG. 2 is a left side view of the fish-holding device for performing tests with fish shown in FIG. 1;

FIG. 3 is a top view of the fish-holding device for performing tests with fish shown in FIG. 1;

FIG. 4 is a bottom view of the fish-holding device for performing tests with fish shown in FIG. 1;

FIG. 5 is a side sectional view of the fish-holding device for performing tests with fish shown in FIG. 1 taken along line A-A as shown in FIG. 1;

FIG. 6 is a perspective view of the fish-holding device for performing tests with fish shown in FIG. 1; and,

FIG. 7 is an exploded view of the fish-holding device for performing tests with fish of FIG. 1.

Right and back side views of the fish-holding device for performing tests with fish are omitted because the right side view and back side view are identical to the left side view of FIG. 2 and the front side view of FIG. 1, respectively. The broken lines shown in FIGS. 1-7 depict the environment in
